UNITED STATES PATENT OFFICE.

NORMAN LEE FRIESE, OF ROANOKE, VIRGINIA, ASSIGNOR TO RAYMOND C. DUDLEY,
OF CHICAGO, ILLINOIS.

CAR-ROOF.

1,074,255.

Specification of Letters Patent. Patented Sept. 30, 1913.

Application filed January 8, 1912. Serial No. 669,938.

To all whom it may concern:

Be it known that I, NORMAN LEE FRIESE, a citizen of the United States, residing in Roanoke, in the city of Roanoke and State of Virginia, have invented a new and useful Improvement in Car-Roofs, of which the following is a specification.

My invention relates to inside metal car-roofs.

10 It has for its object the providing of certain improvements in roofs of the character of that illustrated in the patent to Hodge No. 658,776, of October 2, 1900; and it has for further objects such other improvements 15 in structure or function as may be found to obtain in the devices hereinafter described or claimed.

In the accompanying drawings, forming a part of this specification, and in which like reference numerals indicate like parts in all 20 of the figures, Figure 1 is a transverse sectional view of the roof; Fig. 2 is partly a side elevation and partly a longitudinal section of the roof; Fig. 3 is a section on the 25 line 3—3 of Fig. 1; Fig. 4 is a top plan view showing the end and intermediate construction of the roof and its framework; Fig. 5 is a side elevation with the outer fascia-board removed; Fig. 6 is a side elevation detail to 30 show the lateral grooving and mortising of the ridge pole; Fig. 7 is a perspective view of one of the metallic roof sheets; Fig. 8 is an enlarged detail perspective of the eaves end of one of the intermediate metallic caps; 35 Fig. 9 is a detailed perspective view of the eaves end and ridge end of one of the metallic end caps, with the middle portion of said cap broken away; Fig. 10 is an enlarged detail section on the line 10—10 of Fig. 4; 40 and Fig. 11 is an enlarged detail section on the line 11—11 of Fig. 4.

The roof illustrated in the aforesaid patent to Hodge has been in very extensive use for many years, and certain features of it 45 may be simplified and rendered more effective by the application thereto of the improvements that are the subject of my invention. In the said Hodge construction the metallic roof sheets were held in place at 50 their eaves end, and prevented from slipping out toward the eaves by the stop-blocks illustrated and described in that patent. By my construction, stop-blocks are eliminated and the metal cap-plates alone anchor the 55 metal roofing plates and prevent the latter

from slipping out toward the eaves line, and at the same time the fascia-board of the car receives additional support and yet may be entirely removed without releasing the roofing sheets or affecting their secure retention 60 in proper position, and also the lateral flanges of the sheets are extended out close to the outer fascia and yet provision is made for free drainage of water and discharge of any accumulated cinders from the eaves edge 65 of the body of each sheet and there is further provision for preventing any seepage of water under said eaves edge of the sheet.

The main framework of the roof is constructed of the end plates 20, side plates 21, ridge pole 22, carlines 23, and purlins 24. The inner fascia 25 overlies the upper end of the siding 26. The ridge pole is laterally grooved, at 27, to receive the ridge ends of the bodies of the metallic roofing sheets, and also laterally mortised out, at 28, to receive the ridge ends of the false carlines (termed also sub-carlines) 29 and also the ridge ends of the metallic caps and of the upturned lateral flanges of the metallic roof sheets. The 70 sub-carlines are supported in the mortised out portions of the ridge pole and by the purlins and the side-plates and top edges of the siding and of the inner fascia. The metallic roof sheets 30 have lateral flanges 75 constituted of an upturned bend 31 and outwardly turned bend 32, the latter resting on the upper face of the sub-carlines, the ridge ends of the said sheets and their lateral flanges entering the grooving and mortises 80 of the ridge pole as before mentioned. The sheets have their bodies stiffened by the corrugations 33 extending from the ridge to the inner fascia. The metallic caps overlap the sub-carlines, the flat body 34 of each 85 cap resting on the upper face of the sub-carline and the outer edges of the flanges of the roof sheets, while the down turned lateral flanges 35 of each cap embrace the upturned flanges of the contiguous roof 90 sheets. The longitudinal roof-strips 36 overlie the metallic caps, and spikes 37 are driven through said strips and caps and the underlying sub-carlines, securing said strips in place and at the same time also securing 95 the caps in their proper position; said spikes being, however, clear of any contact with the flanges of the roof sheets, so as not to interfere with any movement of said sheets. The roof boards 38 overlie the ridge 100

pole and roof strips and are extended out over the outer fascia-board 39. The running board saddles 40 and running boards 41 surmount the ridge of the outer board sheathing.

5 The construction described in the last foregoing paragraph has been heretofore well known, and is substantially illustrated in the above mentioned Hodge patent. But 10 in the drawings of said Hodge patent the sub-carlines and the metallic caps and sheets terminate flush with the outer face of the inside fascia-board and entirely clear of the inner face of the outside fascia-board, and 15 the eaves ends of the metallic sheets are held in place by supplementary "stop-blocks", which also serve to space the outer fascia-board from the inner fascia-board, such space permitting the proper drainage of 20 water and discharge of cinders from the eaves ends of the metallic roof sheets. But in the roof shown in my drawings there are various changes in respect to these features. The outer fascia-board is spaced from the 25 inner fascia-board by the spacer-washers 42, through which are passed the tie-rods 43 that parallel each carline and extend from the outside of the outer fascia-board on one side of the car to the outside of the outer 30 fascia-board on the other side of the car. These spacer-washers are entirely free from any contact with the eaves ends of the metallic roofing sheets. The sub-carlines are extended out from the inner fascia- 35 board and nearly into contact with the inner face of the outer fascia-board, and the metallic caps are extended out and bent around the eaves ends of the sub-carlines, so that the eaves ends of said caps, supported 40 against the eaves ends of said sub-carlines, are in direct contact with and additionally support the inner face of the outer fascia-boards. The metallic sheets are increased in length so that the eaves ends of 45 their lateral flanges substantially meet and are retained within and by the closed eaves ends of the metallic caps, such closed ends being formed, as above stated, by the bending of the metal of the caps so as to cover 50 the outer eaves ends of the sub-carlines. The manner of this closure of the ends of the caps, forming a positive means for retaining the eaves ends of the lateral flanges of the sheets, is, that the flat body of the 55 cap is bent over into the down turned flange 44, to cover the eaves ends of the sub-carline, and the lateral down-turned flanges of the cap are extended into tongues 45, 45 which are bent over the down-turned flange 60 44 and mutually lapped at their tips, the said tongues 45 and flange 44 being then permanently and rigidly secured together by the rivet 46, so that there can be no possibility of the opening up of such closed 65 cap-end. To initially secure the cap-end in

position a through-bolt 47 is passed upward through the side-plate and sub-carlines and cap and the overlying longitudinal roof strip.

To provide for the drainage of water and 70 discharge of any accumulated cinders from the body of each roof sheet, and also to additionally prevent the seepage of water under the eaves edge of the roof-sheet, the body of the roof sheet, lengthened as above 75 mentioned, is bent over to form the down turned flange 48 that over-hangs the outer face of the inner fascia-board but leaves a wide, free space between the outer face of such flange and the inner face of the outer 80 fascia-board.

The outer fascia-board may be removed from the car, or damaged or destroyed by side-swiping, without risk of freeing the metallic roof sheets from their proper protective position in the roof. The stop-blocks of the earlier construction are eliminated, and the protective efficiency of the sheets and caps is increased, and at the same time their proper application in the roof is facilitated 85 and insured, as the cap cannot be put in position at all without effecting the proper and permanent retaining of the metallic sheet. 90

95 My invention is above set forth as embodied in one particular form of construction, but I do not limit it thereto or to less than all the possible forms in which the said invention as hereinafter claimed may be embodied and distinguished from prior devices.

100 I claim:—

1. In an inside metal car roof, in combination: a laterally recessed ridge-pole; side plates; sub-carlines supported at their outer ends on the side plates and at their ridge 105 ends in the recesses of the ridge-pole; metallic roof sheets having lateral elevated flanges supported by the sub-carlines, and having their ridge ends entered in the said recesses, the sheets being outwardly slidably transversely of the car; flanged metallic caps fitted over the sub-carlines and over the lateral flanges of the roof sheets, and having their inner ends entered in the recesses of the ridge-pole, and permanently closed at 110 their outer ends, irrespective of attachment to the side of the car, to engage and retain the lateral flanges of the roof sheets and hold the latter at a distance from the fascia, whereby the caps themselves are adapted to 115 serve to securely position the sheets from displacement independently of any eaves fastenings; said fascia opposite to the outer ends of the caps; and spacing means holding the fascia at a distance from the body 120 of the car and from the eaves ends of the roof sheets, substantially as specified.

2. In an inside metal car roof, in combination: a laterally recessed ridge-pole; side plates; sub-carlines supported at their outer 125

ends on the side plates and at their ridge ends in the recesses of the ridge-pole; metallic roof sheets having lateral elevated flanges supported by the sub-carlines, and having 5 their ridge ends entered in said recesses, the sheets being outwardly slidable transversely of the car, and having eaves flanges depending over the edge of the car to protect the latter and aid in the replacement of individual sheets; flanged metallic caps fitted 10 over the sub-carlines and over the lateral flanges of the roof sheets and having their inner ends entered in the recesses of the ridge pole, and permanently closed at their 15 outer ends, irrespective of attachment to the side of the car, to engage and retain the lateral flanges of the roof sheets and hold the latter at a distance from the fascia, whereby the caps themselves are adapted to 20 serve to securely position the sheets from displacement independently of any eaves fastenings; said fascia opposite to the outer ends of the caps; and spacing means holding

the fascia at a distance from the body of the car and from the eaves ends of the roof 25 sheets, substantially as specified.

3. In an inside metal car roof, in combination: a roof-supporting frame; flanged metallic seam caps closed at their eaves ends; metallic roof sheets having upstanding 30 flanges at their sides which are engaged within the said caps and retained by their closed ends; the roof sheets being outwardly and inwardly slidable, for removal and replacement, relative to the said frame, when 35 the outer ends of the said caps are raised; and an outside board roof inclosing and confining the said caps; substantially as specified.

In testimony whereof I have hereunto set 40 my hand in the presence of two subscribing witnesses.

NORMAN LEE FRIESE.
